FIG. 3.

FIG. 4.

UNITED STATES PATENT OFFICE.

OSWALD J. TURNSEK, OF STUTTGART, ARKANSAS, ASSIGNOR TO HYDRAULICS MANUFACTURING CO., OF STUTTGART, ARKANSAS, A CORPORATION OF ARKANSAS.

PUMPING APPARATUS.

Application filed March 30, 1923. Serial No. 628,784.

To all whom it may concern:

Be it known that I, OSWALD J. TURNSEK, a citizen of the United States of America, residing at Stuttgart, in the county of Arkansas and State of Arkansas, have invented certain new and useful Improvements in Pumping Apparatus, of which the following is a specification.

My present invention relates generally to pumping apparatus, and more particularly to pump heads, and proposes a pump rod actuating mechanism by means of which a long stroke reciprocating motion may be developed having special advantage both in regard to the actuation of the pump rod in use and to the maintenance of the pump and the actuating parts against undue wear in use as well as rapid deterioration between periods of operation, my further object being the provision of a compact structure which is readily accessible to and easy and quick repair and substitution of parts as well as an apparatus which readily lends itself to encasement to permit of the running of its main components in a fluid lubricant.

In the accompanying drawings which illustrate my present invention and form a part of this specification,

Figure 1 is a front elevation showing my improved pump apparatus, with the front plate of the casing removed,

Figure 2 is a side elevation,

Figure 3 is an enlarged perspective view of certain parts removed,

Figure 4 is a detail perspective view of a portion of one of the actuating chains, and

Figure 5 is a longitudinal section through the pump rod and its sleeve showing the trunnion connections thereof.

Referring now to these figures and particularly to Figure 1 I have shown my improved apparatus in connection with a pump casing 10 having therein upper and lower plungers 11 and 12, working in opposition to one another, both of these plungers being valved and the lower plunger 12 being mounted upon the lower end of the pump rod 13, while the upper plunger 11 is mounted upon the lower end of a sleeve 14 around the pump rod and through which the latter is movable.

I have also shown the pump casing 10 with a Y fitting 15 at its upper end, the branch 16 of which forms the outlet, and

the upper end of the main section of which supports a stuffing box and the like 17 upwardly through which the sleeve 14 or rather an upper enlarged section 18 of the sleeve 14 works, this upper section being as shown in Figure 3 connected to the lower section 14 by a reducer coupling 19. The rod 13 will also preferably be in two sections of which the upper section is enlarged within the upper enlarged section 18 of the sleeve as indicated at 20.

The upper sleeve section 18 passes through vertical bearings 21 and 22 of the top and bottom plates 23 and 24 of a casing which also includes side walls 25 formed by the upper portions of side frames 26. These side frames are securely mounted at their lower ends upon the side portions of a base plate 27, the latter of which surrounds the stuffing box at the upper end of the pump casing so that the vertically shiftable pump rod and its sleeve will not only be guided in their movement above the ground level or the upper end of the pump casing, but a frame will be formed which, by the addition of front and rear walls in connection with the side walls 25 and the vertically spaced top and bottom plates 23 and 24, become a casing wherein the pump rod and sleeve actuating parts may, to a considerable extent, be completely housed and provision likewise made for the running of these parts in a fluid lubricant.

To this end the side frames 26 have side bearings 28 for a transverse driven shaft 29 the latter of which may be actuated through any suitable connections and from any suitable source of power. This shaft 29 has upon its outer portions, outwardly beyond the bearings 28, small pinions 30 in engagement with comparatively large gears 31 secured upon the outer portions of stud shafts 32 mounted in bearings 33 upon the side walls 25 of the casing and also extending inwardly through these side walls and provided with inner sprockets 34 around which the lower portions of flexible chains and the like 35 extend.

The upper sleeve section 18 has an elongated vertical slot 36 above the upper end of the pump casing, through which a trunnion 37 extends from an attaching plate 38 securely bolted as by means of bolts 39 shown in Figure 5, to the upper rod section 20, said attaching plate 38 and said rod 110

section 20 being provided with relatively engaging cross lugs and slots.

Diametrically outstanding therefrom with respect to its slot 36, the upper sleeve section 18 has a trunnion 40 projecting from an attaching plate 41 which latter is securely riveted to the sleeve as shown in Figure 5.

As seen particularly in Figure 3 the trunnions 37 and 40 are securely fastened to the horizontal bearing end portions 42 of a pair of horizontally disposed cross heads 43 and 44, whose opposite ends have vertical bearing portions 45 disposed on and slideable in connection with a pair of upright guide rods 46, disposed in laterally spaced relation and secured at their upper and lower ends through the top and bottom plates 23 and 24.

Each of the cross heads 43 and 44 has an internal slide block 47 movable therein at right angles to the line of movement of the pump rod, and each cross head also has a detachable rail 48 above its slide block whereby the latter may be readily reached, and wear compensated for. Each slide block 47 has an opening 49, and each of the actuating chains 50 includes in its length a pin block 51 having a laterally projecting pin 52, as most plainly seen in Figure 4, which pin is journaled in the respective slide block opening 49.

The chains 50 which are positioned at opposite sides of the upper portion of the pump rod and its sleeve, and the lower portions of which extend around the before-mentioned sprockets 34, have their upper ends extending around sprockets 53 upon the inner ends of shafts 54 journaled through the side plates 25 of the casing and through bearing members 55 secured to the side walls.

It is thus obvious that as the chains 50 are rotated the cross heads 43 and 44 will be raised and lowered oppositely with respect to one another and corresponding movements communicated to the pump rod and its sleeve whereby the plungers 11 and 12 will be alternately shifted toward and away from one another.

The major portion of the operating parts, that is including the chains 50 and their connections whereby they impart a long stroke movement to the pump rod and its sleeve, are located within the casing and between the top and bottom plates 23 and 24 so that these parts may be conveniently run in oil and yet remain readily accessible for purposes of repair and substitution of parts, these disadvantages being supplemental to and beyond the more important advantages resulting from the application of long stroke reciprocating movements to both the pump rod and its sleeve in the manner I propose, whereby I obtain greater effectiveness and efficiency in operation and at

the same time materially increase the strength and durability of the several parts and promote an apparatus which will be economical in first cost and practically eliminate the expensive upkeep of pumping apparatus now in common use.

I claim:

1. The combination with a lengthwise shiftable rod and a sleeve around the rod, the sleeve having an elongated slot at one side of the rod, trunnions secured to the rod and its sleeve and projecting in diametrically opposite directions, the trunnion of the rod extending through the said slot of the sleeve, a cross head at one side of the rod and sleeve with one end of which the said sleeve trunnion is secured, a second crosshead at the opposite side of the rod and sleeve to which the rod trunnion is secured, guides with which the opposite ends of the cross heads are movably associated, slide blocks working in the cross heads at right angles to the line of movement of the rod, vertically spaced chain supporting sprockets arranged in pairs adjacent to each cross head, means for simultaneously actuating certain of the sprockets of each pair, and chains extending around the said sprockets of each pair, having pin blocks in their lengths provided with laterally outstanding pins journaled in the slide blocks of said cross heads.

2. The combination with a lengthwise shiftable rod and a sleeve around the rod, movable in opposite directions, the upper portion of the said sleeve having an elongated slot at one side of the rod, vertically shiftable cross heads at opposite sides of and in line with the rod and sleeve, one crosshead being connected at one end to the said sleeve and the other crosshead being connected at one end to the rod through the slot of the sleeve, guides on which the cross heads are movable, slide blocks shiftable in the cross heads at right angles to the line of movement of the rod and its sleeve, flexible chains for actuating the cross heads, having laterally projecting pins journaled in the said slide blocks, and connections for supporting and driving the said chains including means for simultaneously moving the chains in relatively opposite directions.

3. The combination with a lengthwise shiftable rod and a sleeve around the rod, movable in opposite directions, the upper portion of the said sleeve having an elongated slot at one side of the rod, vertically shiftable cross heads at opposite sides of and in line with the rod and sleeve, one crosshead being connected at one end to the said sleeve and the other crosshead being connected at one end to the rod through the slot of the sleeve, guides on which the cross heads are movable, slide blocks shiftable in the cross heads at right angle to

- the line of movement of the rod and its sleeve, flexible chains for actuating the cross heads, having laterally projecting pins journaled in the said slide blocks, upper and 5 lower sprockets around which the chains travel, shafts on which said sprockets are secured, gears on certain of said shafts, a driven shaft, and pinions on said shaft in engagement with the said gears whereby 10 to simultaneously drive the chains in relatively opposite directions.
4. A lengthwise movable rod and a sleeve around the rod movable in relatively opposite directions, means for so moving the 15 rod and its sleeve including cross heads immediately adjacent thereto and movable in line therewith, one of which crossheads is attached at one end directly to the rod and the other of which crossheads is at- 20 tached at one end directly to the sleeve, members slidable in the cross heads at right angles to the line of movement of the rod and sleeve, sprocket chains having pivotal connections with said slide members, and 25 means for simultaneously driving the sprocket chains in relatively opposite directions.
5. A lengthwise movable rod and a sleeve around the rod movable in relatively oppo- 30 site directions, means for so moving the rod and its sleeve including cross heads immediately adjacent thereto and movable in line therewith, one of which crossheads is attached at one end directly to the rod
- and the other of which crossheads is at- 35 tached at one end directly to the sleeve, members slidable in the cross heads at right angles to the line of movement of the rod and sleeve, sprocket chains having pivotal 40 connections with said slide members, and means for simultaneously driving the 45 sprocket chains in relatively opposite directions, including sprockets and sprocket shafts and also including a driven shaft having similarly geared connections with certain of said sprocket shafts.
6. A lengthwise movable rod and a sleeve around the rod movable in relatively oppo- 50 site directions, means for so moving the rod and its sleeve including cross heads immediately adjacent thereto and movable in line therewith, one of which crossheads is attached at one end directly to the rod and the other of which crossheads is at- 55 tached at one end directly to the sleeve, members slidable in the cross heads at right angles to the line of movement of the rod and sleeve, sprocket chains having pivotal 60 connections with said slide members, and means for simultaneously driving the sprocket chains in relatively opposite directions, said cross heads including detachable rails whereby the slide members may be removed and wear compensated for.

In testimony whereof I have affixed my 65 signature.

OSWALD J. TURNSEK.
